UNITED STATES PATENT OFFICE.

ROBERT C. LEGAT, OF NEW BRITAIN, CONNECTICUT, ASSIGNOR TO G. E. PRENTICE MANUFACTURING COMPANY, OF NEW BRITAIN, CONNECTICUT, A CORPORATION OF CONNECTICUT.

SHOE FASTENING.

Application filed May 10, 1928. Serial No. 278,650.

This invention relates to fasteners for shoe straps and the like, and the principal object of the invention is to provide a two-part fastener which is simple and economical to manufacture, effective and durable in use, comfortable to the wearer and attractive in appearance.

The improved fastener comprises essentially a buckle member adapted to be secured upon the free end of a strap or tape and a hook member constructed and arranged to engage behind the buckle and to lie under the buckle when so fastened, so that the two parts may readily be attached or separated without threading the strap through a buckle or slider and so that the hook member will be substantially concealed from view beneath the buckle member. When thus assembled the two-part fastener is pleasing in appearance and substantially simulates a single element fastener having a strap threaded through it and retained by frictional or interlocking engagement.

I am aware that two-part fasteners of this general class have heretofore been devised in which a ring member is adapted to slip over and engage behind a buckle member. It is obvious, however, that the closed rings of such fasteners must be substantially wider than the buckle in order that the buckle may be passed through the ring, and that consequently the sides of the ring must necessarily project beyond the sides of the buckle when the parts are attached. Fasteners of this prior type are accordingly awkward to attach and separate and are distinctly displeasing in appearance; and the ring members are not adapted for convenient use with a large-sized buckle.

These and other objects have been overcome by the present invention, recommended embodiments of which are illustrated in the accompanying drawings, wherein:

Fig. 1 is a perspective view of a lady's shoe equipped with one form of the improved fastening;

Fig. 2 is a detail of the hook member shown in Fig. 1;

Fig. 3 is an enlarged bottom view of the buckle member;

Fig. 4 is a section taken on the line 4—4 of Fig. 3, illustrating a strap section threaded therethrough;

Fig. 5 is a similar section showing the

strap section clamped within the buckle and also showing the hook member in the assembled fastening;

Fig. 6 is a plan view of a modified form of hook member;

Fig. 7 is a section on the line 7—7 of Fig. 6, showing a strap end threaded through and frictionally retained by said member; and

Figs. 8 and 9 are top and bottom views, respectively, of an assembled fastening comprising the hook of Fig. 2 and an optional form of buckle.

The fastenings herein illustrated are principally adapted to secure the straps of a ladies shoe across the instep, but the same or similar fastening elements may be employed separately to connect straps or tapes for other purposes and this invention is not intended to be limited to the precise construction or the particular use herein described, except as the invention may be defined in the appended claims.

The slipper or pump 10 illustrated in Fig. 1 has the usual instep strap 11 on one side of the upper and a stub strap 12 on the opposite side. The strap 11 is provided with a buckle member 13 which, for some purposes of the present invention, may be of any desired size or shape and may be permanently or removably secured upon the strap in any desired manner, as long as the hook member may be fastened behind and beneath the buckle in the manner hereinafter set forth. The hook member of Fig. 2 has a curved hook portion 14 and an attachment portion 15 secured to the stub strap 12, and preferably consists of a thin piece of sheet metal suitably stamped out to provide an open slot 16 behind the hook 14 and a closed slot 17 in the attachment portion 15. This type of hook may be attached to the short strap 12 by passing the end of the strap through the slot 16 and fastening the returned end to the strap proper by sewing, as best shown in Fig. 5, or by other securing means.

The particular shape of the hook member is not, however, material to the invention. As illustrated in the modification of Fig. 6, for example, the hook 18 and open slot 19 may be substantially rectangular in outline; and the attachment portion 20 may have a pair of closed slots 21 and 22 sepa-

rated by a cross bar 23. In such case the strap 12 may be frictionally secured to the hook member by threading it upwardly through slot 21 over the bar 23 and downwardly through slot 22, as indicated in Fig. 7.

The two straps are detachably fastened together by slipping the body of the strap 11 transversely into the open slot 16 of the hook member, so that the hook 14 lies upon the outer surface of the strap and is preferably engaged behind the buckle and between the strap and an overhanging edge of the buckle, as shown in Fig. 5. As shown in Figs. 1, 8 and 9, the edge portions of the buckle member overhang the edges of the strap, that is extend beyond the edges of the strap, to cover the projecting portions of the hood. The parts may be thus easily attached or separated by one hand, and it is apparent that the connection may be accomplished irrespective of the size or shape of the buckle; for the hook 14 need only be large enough conveniently to slide over and embrace the strap 11. One unique and meritorious feature of the assembled fastening is characterized by the total concealment of the hook member beneath the buckle, accordingly the relative dimensions of the fastening elements should be such that the hook member is not wider than the buckle member in any corresponding dimension when the parts are fastened together, either longitudinally or transversely of the straps.

It will be observed that the buckle member illustrated in Figs. 3 to 5 is designed to cooperate with the hook member in the manner aforesaid and has certain unique structural features for effecting a secure attachment to the strap 11. The buckle 13 preferably comprises a face plate which may be slightly concaved in one plane and which may be ornamented on its outer surface as desired, an integral downwardly and inwardly inclined loop 24 at one end of the face plate defining a slot 25, and an integral flange 26 returned beneath the plate from its opposite end and having an opening 27 defining a bridge or cross bar 28. A transverse retaining lip 29 preferably projects upwardly toward the bottom of the face plate along the inner edge of the bridge 28, and the free edge of said lip may be serrated if desired.

The flange portion 26 of the buckle is so formed as to be resistantly flexible, whereby its free end may be urged toward or away from the face plate by pressing or pulling the bridge 28 with the fingers to vary the space between the retaining lip and the plate. To attach the buckle to the strap 11, the end of the strap is threaded through the slot 25 and the opening 27 while the lip 29 is spaced appreciably from the face plate as shown in Fig. 4; and the strap is then

securely clamped by pressing upon the bridge 28 so that the lip pinches into the strap as indicated in Fig. 5.

The optional type of buckle shown in Figs. 8 and 9 consists of a metal disc 30 which may be flat or concavo-convex as desired, and which has a pair of spaced parallel slots 31, 32 separated by a cross bar 33. The buckle is frictionally attached to the strap 11 by threading the end of the strap upwardly through slot 31, over the bar 33 and downwardly through slot 32. The hook member has the hook portion 14 and attachment portion 15 and is fastened to the strap 12, as before. When the parts are connected as indicated in Fig. 9, it will be observed that the hook is detachably secured to the strap 11 and is entirely concealed beneath the buckle 30.

A two-part fastening constructed in any of the forms above recommended is simple and inexpensive to manufacture; it furnishes a secure attachment, which is readily assembled and separated, for a variety of articles; and it is pleasing in appearance and lends itself to attractive ornamentation without sacrifice of operative efficiency.

I claim:

1. A fastening of the class described comprising a buckle member adapted to be attached to a strap, and a hook member adapted to be attached to another strap, the hook member having a hook portion hooking edgewise over the first strap and having a slot behind the hook portion thereof adapted to receive the second strap, so that the two straps are connected by engaging the hook portion behind and beneath the buckle.

2. A fastening of the class described comprising a buckle member adapted to be attached to a strap, and a hook member having a hook portion hooking edgewise over said strap and having a slot behind the hook portion thereof adapted to receive the second strap, so that the two straps are connected by engaging the hook portion behind and beneath the buckle member, the longitudinal and transverse dimensions of the hook member being less than the corresponding dimensions of the buckle member and the hook member lying wholly behind the buckle member when the parts are so fastened together.

3. A fastening of the class described comprising a buckle member adapted to be attached to a strap with an edge portion of the buckle member overhanging an edge of the strap, and a hook member having a hook portion hooking edgewise over said strap and having a slot behind the hook portion thereof adapted to receive another strap, said hook portion engaging behind the buckle member and beneath the overhanging edge thereof detachably to connect the two straps.

4. A fastening of the class described comprising a buckle member adapted to be attached to a strap with an edge portion of the buckle member overhanging an edge of the strap, and a hook member having an attachment portion adapted to be connected to another strap and having a hook portion extending edgewise over the first strap, said hook portion engaging behind the buckle member and beneath the overhanging edge thereof detachably to connect the two straps, the transverse dimension of the buckle member being greater than any corresponding transverse dimension of the hook member when the parts are so fastened together.

5. A fastening of the class described comprising a buckle member having a face plate, a downwardly and inwardly inclined loop at one end of said plate and an integral flange returned beneath the plate from its opposite end, said flange having an opening therein and said opening and said loop being adapted to receive and frictionally retain a strap beneath the buckle member with one end of the face plate overlying the outer surface of the strap, and a hook member having an attachment portion adapted to be connected to another strap and having a hook portion adapted to receive the first named strap, said hook portion engaging behind the buckle member and beneath the overlying end of the face plate thereof detachably to connect the two straps, the transverse dimension of the buckle member being greater than any corresponding transverse dimension of the hook member

when the parts are so fastened together.

6. A fastening of the class described comprising a buckle member having a face plate, a downwardly and inwardly inclined loop at one end of said plate and an integral flange at the opposite end of the plate, said flange being returned beneath the face plate and having an opening therethrough and a bridge at its free end carrying an upstanding transverse lip, said flange being flexible whereby the buckle member may be clamped upon a strap passing through said loop and said opening by pressing the bridge toward the under side of the strap, and a hook member attached to another strap element and having a slot behind the hook portion thereof adapted to receive the second named strap, said hook portion engaging between said flange and said first named strap and being narrower than the face plate directly above it, detachably to fasten the parts together with the hook member concealed beneath the buckle member.

7. A fastening of the class described, comprising a buckle member adapted to be attached to a strap with the edge portions of the buckle member overhanging the edges of the strap, a hook member having a hook portion hooking edgewise over said strap, and means for attaching the hook member to another strap, said hook portion engaging behind the buckle member and beneath the overhanging edges thereof detachably to connect the two straps together.

Signed by me at New Britain, Conn., this seventh day of May, 1928.

ROBERT C. LEGAT.
